US0D1113474S

(12) **United States Design Patent** (10) **Patent No.:** **US D1,113,474 S**
Yuanyuan et al. (45) **Date of Patent:** **** Feb. 17, 2026**

(54) **TEMPERATURE CONTROLLER**

(71) Applicants: **Shen Yuanyuan**, Shenzhen Guangdong (CN); **Lin Chuqiao**, Shenzhen Guangdong (CN)

(72) Inventors: **Shen Yuanyuan**, Shenzhen Guangdong (CN); **Lin Chuqiao**, Shenzhen Guangdong (CN)

(73) Assignee: **Shenzhen M&F E-Commerce Co., Ltd.**, Shenzhen (CN)

(**) Term: **15 Years**

(21) Appl. No.: **29/895,224**

(22) Filed: **Jun. 19, 2023**

(30) **Foreign Application Priority Data**

Jun. 1, 2023 (CN) 202330332259.6

(51) LOC (15) Cl. **10-04**

(52) U.S. Cl.

USPC **D10/50; D7/603**

(58) **Field of Classification Search**

USPC D10/49, 50; D7/603

CPC F25D 31/007; F25D 2331/809; F25D 2331/805

(57) **CLAIM**

The ornamental design for a temperature controller as shown and described.

DESCRIPTION

FIG. 1 is a front perspective view of a temperature controller according to our new design;

FIG. 2 is a bottom perspective view thereof;

FIG. 3 is a right side view thereof;

FIG. 4 is a left side view thereof;

FIG. 5 is a front side view thereof;

FIG. 6 is a rear side view thereof;

FIG. 7 is a top side view thereof;

FIG. 8 is a bottom side view thereof;

FIG. 9 is a closeup view of a section of FIG. 1;

FIG. 10 is a front perspective view of the temperature controller of FIG. 1 in a first configuration of use; and,

FIG. 11 is a front perspective view of the temperature controller of FIG. 1 in a second configuration of use.

The broken lines are included for the purpose of illustrating portions of the temperature controller that form no part of the claimed design.

1 Claim, 11 Drawing Sheets
